(57) **CLAIM**

The ornamental design for an electric terminal as shown and described.

DESCRIPTION

FIG. 1 is a front perspective view of an electric terminal according to the present invention according to a first embodiment.

FIG. 2 is a rear perspective view of the electric terminal of FIG. 1.

FIG. 3 is a right side view of the electric terminal of FIG. 1.

FIG. 4 is a left side view of the electric terminal of FIG. 1.

FIG. 5 is a bottom view of the electric terminal of FIG. 1.

FIG. 6 is a top view of the electric terminal of FIG. 1.

FIG. 7 is a front view of the electric terminal of FIG. 1, the rear view being a mirror image thereof.

FIG. 8 is a front perspective view of an electric terminal according to the present invention according to a second embodiment.

FIG. 9 is a rear perspective view of the electric terminal of FIG. 8.

FIG. 10 is a right side view of the electric terminal of FIG. 8.

FIG. 11 is a left side view of the electric terminal of FIG. 8.

FIG. 12 is a bottom view of the electric terminal of FIG. 8.

FIG. 13 is a top view of the electric terminal of FIG. 8; and,

FIG. 14 is a front view of the electric terminal of FIG. 8, the rear view being a mirror image thereof.

The broken lines illustrate portions of the electric terminal that form no part of the claimed design.

1 Claim, 14 Drawing Sheets
